H. W. TINKER

FENDER GUARD FOR VEHICLES

Filed Oct. 30, 1925

INVENTOR:

Herbert W. Tinker

By Reeder, Hobbs, Davis and Macander

Attn: [unclear]

UNITED STATES PATENT OFFICE.

HERBERT W. TINKER, OF MILWAUKEE, WISCONSIN, ASSIGNOR TO FEDERAL PRESSED STEEL COMPANY, OF MILWAUKEE, WISCONSIN, A CORPORATION OF WISCONSIN.

DESIGN FOR A FENDER GUARD FOR VEHICLES.

Application filed October 30, 1925. Serial No. 15,294. Term of patent 14 years.

To all whom it may concern:

Be it known that I, HERBERT W. TINKER, a citizen of the United States, residing at Milwaukee, in the county of Milwaukee and State of Wisconsin, have invented a new, original, and ornamental Design for Fender Guard for Vehicles, of which the following is a specification, reference being had to the accompanying drawings, forming part hereof.

Figure 1 is a perspective view and Figure 2 a rear elevation of a fender guard for vehicles showing my new design.

I claim:

The ornamental design for a fender guard for vehicles, as shown.

HERBERT W. TINKER.
